[57] CLAIM

The ornamental design for a modular control unit housing for an electrical protection system, as shown and described.

DESCRIPTION

FIG. 1 is a front perspective view of a modular control unit housing for an electrical protection system embodying my new design;

FIG. 2 is a front elevation of the housing of FIG. 1 on an enlarged scale;

FIG. 3 is a side elevation as viewed from the right side of FIG. 2 on an enlarged scale;

FIG. 4 is a top plan view of the housing of FIG. 1 on an enlarged scale;

FIG. 5 is a rear elevation of the housing of FIG. 1 on an enlarged scale;

FIG. 6 is a bottom plan view of the housing of FIG. 1 on an enlarged scale;

FIG. 7 is a side elevation as viewed from the left side of FIG. 2 on an enlarged scale;

FIG. 8 is a front perspective view of a modular control unit housing for an electrical protection system showing a second embodiment of my new design;

FIG. 9 is a front elevation of the housing of FIG. 8 on an enlarged scale;

FIG. 10 is a front perspective view of a modular control unit housing for an electrical protection system showing a third embodiment of my new design;

FIG. 11 is a front elevation of the housing of FIG. 10 on an enlarged scale;

FIG. 12 is a front perspective view of a modular control unit housing for an electrical protection system showing a fourth embodiment of my new design; and

FIG. 13 is a front elevation of the housing of FIG. 12 on an enlarged scale.
